WHEEL

Donald J. Reid, Pleasant Ridge, Mich., assignor to Kelsey-Hayes Company, Romulus, Mich., a corporation of Delaware

Filed Dec. 20, 1965, Ser. No. 251

Term of patent 14 years

(Cl. D14—30)

The dominant features of my design reside in the portions shown in full lines, said features being characterized by color contrast indicated by the shaded and unshaded portions.

I claim:

The ornamental design for a wheel, substantially as shown and described.
